UNITED STATES PATENT OFFICE.

CHARLES P. GAY, OF PROVIDENCE, RHODE ISLAND.

SASH-HOLDER.

SPECIFICATION forming part of Letters Patent No. 373,824, dated November 29, 1887.

Application filed December 14, 1886. Serial No. 221,520. (No model.)

To all whom it may concern:

Be it known that I, CHARLES P. GAY, a citizen of the United States, residing at Providence, in the county of Providence and State 5 of Rhode Island, have invented certain new and useful Improvements in Double-Acting Sash-Holders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain novel improvements in double-acting sash-holders; and it consists, essentially, in the combination, with an angular base-plate and spring actuated arms or dogs pivoted therein, of a slightly- 20 elastic cap inclosing the working-face of each arm and an adjustably-mounted screw adapted to lock the arm in position.

The object of my present improvements is to provide the upper and lower weighted 25 sashes of windows with means whereby both sashes may be more readily adjusted and effect- ually locked in position.

In the accompanying sheet of drawings, illustrating my invention, Figure 1 represents 30 a plan view of the device attached to the top surface of the lower weighted sash, the upper sash and window-casing being shown in horizontal section. Fig. 2 is a side view of the same, showing one of the elastic caps in section 35 and bearing against the upper sash as in use. Fig. 3 is a front view showing the other working-arm bearing against the inner vertical face of the casing. Fig. 4 is a vertical longitudinal sectional view taken through $x x$ of Fig. 1, 40 with the auxiliary locking device and one arm removed, the elastic cap being in elevation. Fig. 5 is a detached perspective view of the elastic cap. Fig. 5 $\frac{1}{2}$ is a partial transverse sectional view taken on line $o o$ of Fig. 4. Fig. 45 6 is a transverse sectional view, showing a modified form of the device for locking the arm in position; and Fig. 7 is a plan view thereof.

The following is a more detailed description 50 of the invention, including the manner of its operation.

A, referring to the drawings, designates my improved double-acting sash-lock as a whole. a indicates the metallic base-plate, the same having an angular form or outline (see Fig. 1) 55 and provided with the two sets of vertical sides a', arranged at right angles to each other and having pins p therein. The front end portions of the angular base are slightly raised and provided with openings h, adapted to receive the bent end e' of the flat metal spring e, (one being shown in Fig. 4.) B B designate the arms or dogs pivoted to the base-plate a by means of said pins p. The front or free end, b², of each arm is made slightly eccentric and 60 somewhat elongated, the circumscribing faces of the said elongated portion b² being beveled (see Figs. 2 and 5 $\frac{1}{2}$) to form a better holding-surface for the removable caps, about to be described. The rear ends, b, of the arms are 70 flattened, which, in connection with the springs e, prevent them from accidentally falling. (See dotted position, Fig. 4.) The free end of the arm is elongated, as at b⁴, for the purpose of affording a convenient handle to take hold of 75 in disengaging or unlocking the arm from the window casing or jamb.

C indicates the cap, made of stiff rubber or other suitable material possessing slightly-elastic properties. The cap is made hollow 80 or chambered, as at c, to fit the said beveled portion b² of the arms, the contracted sides of the cap being sprung over the same. The working-face c² of the cap is slightly roughened or corrugated, its contour closely following 85 that of the adjacent portion of the arm.

On the inner side of one of the holders is formed a projection, n, which is tapped to receive a screw, D, the head of the latter being elongated to extend over the top of the adjacent arm. (See first three figures.) By means 90 of this attachment the sash, supported by said arm, is prevented from being lifted, while at the same time the eccentricity of the arm precludes its being forced downward.

In Figs. 6 and 7 I have shown a modified form of the locking device, the same consisting of the loose plate D', through which a screw, r, loosely passes to engage the tapped boss n, the nut r² serving to clamp the plate in 100 position over the arm B.

Now, assuming the improved sash-lock A

to be secured to the lower sash, as represented, the manner of its operation is substantially as follows: When used as a lock to keep the upper and lower sashes closed, the two arms B B 5 are dropped, one to engage the upper sash, s', and the other to engage the casing or window-jamb F, the compressible caps C being directly in contact with said sash and casing. Of course any upward pressure applied to the 10 lower sash tends to more firmly lock the parts together.

It is obvious that by swinging the arms B upward (see dotted position, Fig. 4) either or 15 both sashes may be moved up and down, as desired, after which, when the proper adjustment has been attained, the sashes are locked in position by simply dropping the arms B into engagement with the respective sash and jamb. The arm bearing against the upper 20 sash is then more effectually retained in position by turning the head of the screw D partly around, so that its under side engages with the upper surface of the arm.

By means of this auxiliary locking device 25 it is rendered impossible to unlock the sash from without by inserting a thin piece of metal between the two sashes against the holding-arm.

The removably-secured elastic cap C fur- 30 nishes a comparatively large bearing-surface, the internal shape being such that the cap re-

mains in position upon the arm, even under great pressure.

I do not claim, broadly, a double-acting sash-lock; but

What I do claim, and desire to secure by United States Letters Patent, is—

1. The angular double-acting sash-lock hereinbefore described, consisting of the base-plate, locking-arms mounted at right angles to each other in said plate, removably-secured semi-elastic caps adapted to engage the sash and jamb, covering the working-face of the arms, an auxiliary locking device or devices adapted to retain the arms in the locked position, and springs adapted to hold the arms in the normal or unlocked position, the whole constructed, arranged, and operating substantially as shown and set forth. 40

2. The combination, with the angular base 50 and arms B B mounted therein at right angles to each other, of the auxiliary locking device consisting of an adjustably-mounted screw having its head elongated to engage the arm B, substantially as shown, and for the purpose 55 hereinbefore set forth.

In testimony whereof I have affixed my signature in presence of two witnesses.

CHARLES P. GAY.
